UNITED STATES PATENT OFFICE.

BLAKE WILLIAM GARDNER, OF MEMPHIS, TENNESSEE.

AUTOMATIC STOPPING ATTACHMENT FOR PHONOGRAHS.

Application filed June 18, 1920. Serial No. 389,896.

To all whom it may concern:

Be it known that I, BLAKE WILLIAM GARDNER, a citizen of the United States, residing at Memphis, in the county of Shelby 5 and the State of Tennessee, have invented a new Automatic Stopping Attachment for Phonographs.

My invention relates to stopping devices for phonographs or talking machines and 10 has for an object to provide an improved construction and arrangement of elements which used in conjunction with two moving parts of a phonograph, will effect an automatic stopping of the machine when the 15 stylus, carried by the tone arm reaches the end of record groove, and itself stops moving.

Another object is to provide accuracy in 20 operation, simplicity in construction and to reduce to a minimum the resistance or impelling pressure on the tone arm through 25 operation of the attachments.

Another object is to produce a stopping device which requires no skill or knowledge 30 of the working parts to enable any one to set the mechanism and which requires no attention when once put into action.

I attain these and other objects by the 35 mechanism illustrated in the accompanying drawing which shows a practical embodiment of my invention, and in which—

Figure 1 is a top plan view of the device 40 showing the necessary coacting parts in their relative positions while the record is being played.

Figure 2 is a side elevation showing the parts that are closely associated with the tone arm.

Figure 3 is a fragmentary view showing 45 in plan, the escapement and its tripping device.

Figure 4 is a fragmentary view in plan and enlarged showing the tone-arm properly located and relative position of the pin 39 50 and the turntable.

In the drawings 1 represents the lower member of a two part friction-jointed lever having a slot 2 for connection to a tone arm 38 by means of pin 39 (see Fig. 2). The 55 lower portion of said lever contains a stationary disk 3 and pin 5 with a disked washer beneath the pin to produce slight friction at the joint. The cut away portion 4 on disk 3 is designed to operate a tension lever 7 which carries the plate spring 9, the free end of said spring 9 acting to repel

alternating or vibrating lever 10 at all times except while the tone arm is travelling within 3½ inches from the center of the record. Therefore no stopping of phonograph 60 can take place unless the tone arm, or rather, the stylus pin is within 3½ inches from the center of the disk record. At this point tension lever 7 will enter cut out 4 in disk 3 and release pressure by spring 9 against lever 65 10 and allows lever 10 to remain under control of repelling bar 40. Repelling bar 40 is rigidly attached to lever 8. The upper member 8 of jointed lever is pivoted and bridged at its extreme end by bridge 11. 42 70 is a guide bridge which retains lever 8 in position but affording a slight swinging movement to insure correct action against lever 10 by bar 40; this action is secured by means of pivoting lever 8 at its extreme 75 upper end to the bridge 11, and the correct action upon friction joint is secured, which is free from any recoil.

Alternating or oscillating lever 10 is pivoted at its lower end into one end of a rocking brake lever 24, and is held to correct 80 position by a guide 12 containing a slot which permits the lever 10 to oscillate or vibrate above escapement wheels 13 and 14, but not in contact with said wheels, except 85 through cam 19 or trip pin 20. When said lever 10 is repelled or forced outwardly by action of the pin 20 on the rotating escapement wheel 14 it tilts or rocks lever 24 which pushes up lever 26, this lever 26 having a 90 lug 27 on its underside which strikes the brake lever latch 22, releasing the tail piece 30 on the brake arm 31, which the spring 29 95 rotating the lever, forces the brake shoe 32 against the downwardly hanging flange on the turn table of the machine.

23 represents the pivot for lever 22, and 100 29 is a spring which holds latch lever 22 in set position and also holds the brake shoe inactive.

Lever 26, which is a lifting lever or bar, is provided as stated, with a lug 27, which 105 engages lever 22, and passing through a guide 28 extending upwardly from the base plate 35.

The only gear wheels above the base plate 35 are trip wheel 14, which turns to the right, and the cam wheel 13 which turns to the left, these wheels meshing, and constituting, with the vibrating lever 10, carrying 110 19 the escapement device.

The driving mechanism for the device includes four gears only and the two escapement wheels, the gear wheel 18 which fits over the center post of the phonograph has 5 25 teeth and meshes with gear 17 having 50 teeth; on the same shaft or arbor with gear 17 is the gear 16 having 18 teeth and meshing with gear wheel 15. On the shaft of gear 15 is the smaller escapement gear wheel 14 which as stated before 10 meshes with gear 13 carrying the cam 19. Thus the gear wheel over post of the phonograph with two other wheels and the pinions 15, 16 and 17 complete the gear into 15 an escapement gear causing one turn of the escape wheels to three revolutions of the center post.

The operation of the control lever and its particular design are very important, as it 20 will be noted that it is free only to pivot at its extreme end. With the tone arm pin 39 operating in slot 2 and repelling bar 40 at center of lever, said control lever forms a leverage at bar 40, and thus will be secured 25 twice the resistance for repelling lever 10 through 40 that would be applied against tone arm in carrying up the lever 1.

When the tension lever 7 and spring 9 are 30 in the position shown in Fig. 4, the tone arm is at outer side of the record and tension lever 7 is forced to outer rim of the disc 3, applying spring 9 against lever 10 and holding it out of tripping position at all 35 times, except, when released by means of cut out 4 on disk 3, which the tension lever 7 enters while the stylus is about three and one half inches from center of record, or beyond the point where the farthermost record grooves end, and the lever 10 should be over 40 at the right of the slot in guide 12 and free from the action of the tripping pin 20.

In Figure 3 is shown the cam 19 repelling lever 10 into tripping position with tripping pin 20, escaping beneath the hook provided 45 on lever 10. If now at this point the tone arm has reached the innermost circle where said arm stops, travelling toward the center post, lever 10 will remain in the position placed by the cam, and tripping pin 20 will 50 enter the hook and repel or force lever 10 outwardly rocking lever 24, lifting brake restraining lever 22 and releasing the tail piece 30; the spring 29 then acts to swing the brake arm on the fulcrum and forcing 55 the brake shoe 32 against the turn table, cause the phonograph to stop.

If the stylus has not reached the innermost circle, then lever 10 will move to the right and pin 20 will escape the hook, as in 60 Fig. 3.

When the lever 10 is repelled or forced outwardly by the action of trip pin 20 in releasing the brake, spring 25 will repel all the levers to their setting position against 65 bumper 41.

No special movements or knowledge of the operation of this device are required. The brake lever is released by the gears connected up with the center post of the machine, while the vibratory end of lever 10 extending into the escape gears is controlled and held out of actuating position by the slotted lever section 1, which is connected with the tone arm 38 through the pin 39 and said section is carried up by the pin as the record is being played, causing a steady pressure through the repelling bar at the joint of the lever sections against the tripping oscillating lever 10, consequently the tone arm must stop travelling toward the center before a cut off or stopping of the machine can be effected.

So long as the tone arm travels toward center of the record, repelling bar 40 continually causes the lever or trip bar 10 to be free from tripping action; when the tone arm stops, the cam 19 then comes into engagement with the trip bar 10 and holds it in position during one complete revolution of the record.

For lack of space the lower portion of control lever is shown slanting to the right, but it should have about an equal slant to the left when connected with the tone arm.

Having thus fully described my invention and the means by which it is to be carried into effect, what I claim is:

1. In a talking machine, a turn table, a tone arm, a sectional control lever coacting with said tone arm, a stop on said control lever, a tension lever fulcrumed on the one section of said control lever, means for moving the other section of said control lever in one direction during and with the movement of the tone arm toward the center of the turn table, a spring actuated brake lever carrying a brake shoe adapted for engagement with said turn table, a tripping lever normally held inactive by said tension lever during travel of the tone arm toward the center of the turn table, a trip escapement driven from the spindle of said turn table, and adapted to coact with said trip lever when the movement of the tone arm ceases, and an intermediate and interconnected system of levers interposed between said tripping lever and the brake lever whereby to release the brake and apply the same to the turn table upon stoppage of movement of the tone arm toward the center of the same.

2. In an automatic stop for phonographs, the combination of a brake, a spring tending to apply the brake, a detent for holding the brake in off position, a reciprocatory brake releasing rod movable longitudinally into and out of position to engage and to release said detent from the brake lever, a tripping escapement gear driven by the spindle of the turn table of the machine, a trip lever adapted to be actuated by said

escapement, and means actuated by the tone arm and tending when the stylus is traversing a record to shift said trip lever out of operative position, said means including a 5 sectional control lever and an impelling bar carried and actuated thereby and adapted to engage said trip lever.

3. In an automatic stop for phonographs, the combination of a brake, a spring tending normally to apply said brake, a detent 10 for holding said brake in inoperative position, a sectional control lever, the sections connected at opposite ends by a friction joint, the one section pivotally anchored at 15 one end, a tension lever pivotally secured to said section adjacent the said joint, the other section provided with a longitudinal guideway, a stop carried by the guideway section at said joint and adapted to control 20 said tension lever, a tone arm, a pin projecting from said tone arm and adapted for engagement with said guideway, an escapement geared with the spindle of the turn 25 table of the phonograph, a trip lever engageable by said escapement, an impelling bar carried by the first named section of the control lever, and levers interconnected with 30 said trip lever and the brake detent, the stoppage of movement of the tone arm toward the center of the record causing the 35 tension lever to permit the trip lever to be moved into the path of movement of the escapement and be impelled by said escapement to release said detent and apply the brake.

4. In an automatic stop for phonographs, the combination of a brake, a spring tending to apply the brake, a detent for holding the 40 brake in off position, a reciprocating brake releasing rod movable longitudinally into and out of position to engage and release 45 detent, an escapement train driven from the

spindle of the turntable of the machine, a vibratory trip lever adapted to be tripped by said escape, and means actuated by the 45 tone arm, to cause the trip lever to move to tripping position, said means including a sectional control lever, a tension lever carried by one section thereof, and contacting with said trip lever and an impelling bar 50 carried by the control lever.

5. In an automatic stop for phonographs, a turn table, a tone arm, a control lever coacting with the tone arm, an escapement train driven from the spindle of the turn 55 table, a brake, a spring tending to apply said brake, a latch for holding said brake in off position, a vibratory and longitudinally movable trip lever, means for causing the escapement to actuate said trip lever in 60 its longitudinal direction, and means actuated by the longitudinal movement of the trip lever, to release said latch and apply the brake to the turn table, said means comprising an intermediate and interconnected system of levers interposed between the trip lever and brake lever. 65

6. In a talking machine including a turntable, and a tone arm, a jointed control lever coacting with the tone arm, an escapement driven from the spindle of the turn table, a spring actuated brake, a latch for holding said brake in off position, a vibratory and longitudinally movable trip lever, said lever being straight and pivoted at one 70 end and having a trigger at its other end, a rocking lever pivotally connected to said straight lever paralleling said control lever and mediating escapement, and means for causing the escapement to actuate the trip 75 lever in its longitudinal direction and through the rocking lever to release the aforesaid latch. 80

BLAKE WILLIAM GARDNER.
